SHOWCASE REFLECTOR

Reuben B. Benjamin, Chicago, Ill., assignor to
 Benjamin Electric Manufacturing Company,
 Chicago, Ill., a corporation of Illinois

Application April 12, 1930. Serial No. 443,672

5 Claims. (Cl. 240—6)

This invention relates to electric lighting fixtures and has special reference to an electric lighting fixture for use in show cases, and the like.

5 More particularly this invention has reference to a lighting fixture for use in show cases and the like comprising a receptacle member, a casing, a reflector and positioning clips, which fixture is particularly suitable for use in curved sections 10 of show cases.

An object of this invention is to provide a show case lighting fixture comprising few parts which may be easily and quickly assembled. The casing is provided with an inwardly projecting portion 15 at one end thereof over which is placed one end of the reflector. The receptacle member projects over the other end of the reflector and securely holds the reflector in the casing, and is, in turn, secured to the casing by means of a single screw. Thus, in order to assemble the fixture it is merely necessary to hook one end of the reflector over the inwardly projecting portion and then tighten the one screw which secures the receptacle member to the casing.

20 A further object of this invention is to provide a lighting fixture of the type above referred to which is compact and therefore particularly adapted for use in curved portions of a show case. The bushings on the inside of the casing for receiving the lead wires or conduits carrying the lead wires are set in the rounded end portions of the casing adjacent the top thereof so as not to extend outwardly beyond the bottom of the end portions of the casing.

25 A still further object of the invention is to provide a lighting fixture in which is attached a lamp socket having a flared receiving opening whereby a lamp may be inserted therein by a simple swinging movement without the necessity 30 of the usual screwing-in operation and which, when inserted, is held in contact position by a resilient clip.

A still further object of the invention is to provide a lighting fixture having positioning clips 45 which secure the fixture in a show case or the like and focus said fixture at a proper illuminating angle.

A still further object of the invention is to provide a lighting fixture having a feed-through circuit to which a lamp socket may be electrically connected without the necessity of breaking or cutting the lead wires.

Further objects and advantages of the present 50 invention will be more readily understood by ref-

erence to the following description, together with the accompanying drawings, in which latter:

Figure 1 is a vertical cross-sectional view of a lighting fixture embodying this invention with a lamp attached therein;

Fig. 2 is a face view of a lighting fixture embodying this invention;

Fig. 3 is a top plan view of the receptacle member showing the wiring terminal screws positioned in grooves;

Fig. 4 is a horizontal cross-sectional view of the receptacle member showing the base of the lamp in contact with the receptacle contacts;

Fig. 5 is a cross-sectional view taken on the line 5—5 of Fig. 1;

Fig. 6 is a perspective view of the side and center contacts of the receptacle showing the protruding threaded portion which engages the terminal wiring screws;

Fig. 7 is a cross-sectional view taken on the line 7—7 of Fig. 1 showing the casing, the reflector, the end of the bushing and the lamp securing clip;

Fig. 8 is a vertical cross-sectional view of a modification of this invention showing a double socket reflector;

Fig. 9 is a view of the receptacle contacts employed in the double socket;

Fig. 10 is a plan view of the fixture positioning clip attached to the front side of a show case or the like;

Fig. 11 is a modified view of an adjustable positioning clip attached to the front side of a show case or the like; and

Fig. 12 is a perspective view of a section of a show case with a fixture embodying this invention connected in assembly with other show case lighting fixtures by means of conduits.

Referring to the drawings in detail, the construction shown comprises a lighting fixture for use in show cases and the like made up of a trough-like casing 1 having end portions which extend vertically downward adjacent the top of the casing and then are rounded so as to flare outwardly at the bottom. In the end portions of the casing adjacent the top are circular holes 2 through which are extended the reduced portions 3 and 4 of the bushings 5 and 6. The reduced portion 4 of the bushing 6 is bent outwardly against the inside of the casing so as to hold the bushing in place. Likewise, the reduced portion 3 of the bushing 5 is bent outwardly against the other end of the casing except for the shelf portion 6' which extends horizontally inside the casing. Conduits 7 fit into the bushings 5 and 6 and

are held in place therein by means of the screws 8.

A rounded trough-like reflector member 9 open at both ends and adapted to lie adjacent the sides of the trough-like casing 1 is placed inside 5 the casing with one end hooked over the shelf portion 6' of the bushing 5. The receptacle member 10 is then positioned in the casing at the end opposite the shelf 6 so that the inside end thereof extends over the end of the reflector 9. 10 The screw 11 is threaded into the screw receiving member 12 which is fastened to the top of the casing 1 by riveting or other desirable means. Thus, one screw suffices to hold the reflector and receptacle in position within the casing.

15 The receptacle 10 is formed with a lamp receiving recess 13, one side of which is flared at 14 as shown in Fig. 1, so that a lamp may be inserted therein by a simple swinging movement without the usual screwing-in operation. When the 20 base of a lamp has been inserted in the lamp receiving recess 13, the lamp is maintained in contact position by means of a securing clip 15, fastened to the end of the casing over the reduced portion 3 of the bushing 5. This clip 15 comprises a downwardly extending strip 16, which 25 may be of metal or any other desirable material having an enlarged end portion with a hole therein which end portion is bent up and inside the casing at 17 as shown in Figures 1 and 7 and 30 engages the bulb end of the lamp when the same is swung upwardly into contact position.

The receptacle 10 has side and center contacts adapted to engage respectively the side and center contacts of the lamp to be inserted there- 35 in. The side contact 18 is formed of a strip of conducting material having one end doubled back inside the recess 13, as shown in Figs. 4 and 6, so as to engage the side contact of the lamp, and the other end extends back into the receptacle and is provided with a threaded portion 19 which extends in a plane at right angles to the plane of said strip. The center contact 20 also shown in Figs. 4 and 6 is formed of a strip of conducting material bent substantially in a right 40 angle, one end of which lies adjacent the end of the lamp receiving recess 13 so as to engage the center contact of the lamp and the other end of which extends back into the receptacle and is likewise provided with a threaded portion 21 extending in a plane at right angles to the plane of the strip 20. If the double socket shown in Fig. 8 is used the contacts shown in Fig. 9 are em- 45 ployed. The side contact is formed of a strip of metal 22, the ends of which are doubled back 50 inside the recess and has a threaded portion 23 intermediate the ends thereof extending in a plane at right angles to the plane of the strip. The center contact is formed of a U-shaped strip 55 of conducting material 24, which is provided with a threaded portion 25 intermediate the ends thereof extending in a plane at right angles to the plane of said strip. Grooves 31 are provided 60 in the top of the receptacle 20 for receiving the lead wires of the fixture which wires are held 65 in place in the grooves by the head of the wiring terminal screws 32. These screws thread into the threaded portions of the contacts 18 and 20 thereby forming an electrical connection between the lead wires and the receptacle contacts.

70 The whole fixture is secured in a show case or the like by means of positioning clips 26 which are preferably fixedly secured to the casing, as shown in Fig. 10, although they may be adjustable, as shown in Fig. 11. These clips 26 com-

prise a flat metal portion 27 which fits against the vertical part of the end portions of the casing 1. This portion 27 is provided with a flat edge 28 adapted to lie against the inner surface of the top of the show case or the like so as to focus the fixture at a proper illuminating angle. Integrally formed with the portion 27 is a strip 29 lying in a plane at right angles to the strip 27. This strip 29 is adapted to lie against the front of the show case or the like and to be bent over the top thereof, as shown in Figs. 10 and 11. By means of this clip the fixture is both securely held to the show case in which it is to be used and is at the same time properly focused. The modification of the positioning clip shown in Fig. 11 is similar to that shown in Fig. 10 except that it is cut substantially straight across at 30 so that it may be adjusted without striking the rounded end of the casing 1.

90 In assembling the fixture one end of the reflector 9 is hooked over the shelf portion 6 of the bushing 5 and the receptacle extending partly over the other end of the reflector is then fastened to the other end of the casing by means of the screw 11. The lead wires which extend 95 through the space between the casing 1 and the reflector 9 are bared above the receptacle. The bared portions are bent down so as to lie in the grooves 31 under the heads of the terminal wiring screws 32. The wiring screws 32 which extend 100 downwardly through the top of the receptacle 10 engage the threaded portions 19 and 21 of the side and center contacts 18 and 20. The fixture is now ready to be placed within the show 105 case in which it is to be used. The strips 29 of 110 the clips 26 are placed against the inside of the front of a show case, after which they are bent over the top of the show case so that the flat portion 28 lies adjacent the top of the show case. A lamp is inserted by placing the base thereof 115 in the flared receiving entrance of the receptacle recess 13 and swinging the other end of the lamp upwardly so as to engage the opening in the lamp securing clip 15. The fixture is then ready for 120 use.

125 While I have shown and described but two embodiments of this invention, it is to be understood that various modifications thereof will be apparent to those skilled in the art without departing from the spirit and scope of this invention and, therefore, the latter is to be limited only by the scope of the prior art and the appended claims.

I claim:

1. A lighting fixture for use in show cases 130 and the like, comprising a trough-like casing having outwardly tapering ends, a reflector lying within said casing, a receptacle for receiving the base of a lamp to be inserted therein secured with- 135 in said casing, and bushings for receiving conduits attached to said casing at the top of each end thereof and extending through openings in said casing so as not to extend outwardly beyond the bottom part of said end portions.

2. A lighting fixture for use in show cases and 140 the like, comprising a casing, a bushing in one end of said casing for receiving a conduit, said bushing having an inwardly projecting portion, a reflector fitting over said projecting portion, and a receptacle secured in the opposite end of said 145 casing, said receptacle fitting under the other end of said reflector to support the same.

3. The combination with a trough-like casing, of a lamp receiving receptacle for supporting a lamp in said casing comprising an insulating base 150

having a lamp receiving recess, said base having an opening in the upper part thereof for receiving a screw to be threaded into said casing, and an enlarged opening below said slot whereby the screw 5 may be inserted from below said receptacle to secure the receptacle to the casing.

4. A show case lighting fixture comprising a trough-like casing, a trough-like reflector member housed thereby, an insulating member secured 10 in said casing having an unthreaded recess for receiving the base of a lamp and having side and bottom contacts adapted to engage respectively the side and center contacts of said lamp, said side contact being resiliently positioned in said 15 recess at one side thereof, and said insulating member having an inserting entrance flared on the side remote from the reflector sufficiently to enable the lamp to swing outwardly when fully inserted without substantial axial movement 20 whereby a lamp may be inserted therein by placing the lamp base in the inserting entrance of said insulating member and swinging the bulb end of said lamp inwardly into said casing, a threaded anchorage member secured to said contact, and a binding screw for said contact having its head at the rear of said insulating base 25 and its shank extending forwardly therefrom

whereby the wiring extending longitudinally of the casing may be caught under the head of the screw.

5. A show case lighting fixture comprising a trough-like casing, a trough-like reflector member housed thereby, an insulating member secured in said casing having an unthreaded recess for receiving the base of a lamp and having side and bottom contacts adapted to engage respectively the side and center contacts of said lamp, said first side contact being resiliently positioned in said recess at one side thereof, said insulating member having an inserting entrance flared on the side remote from the reflector sufficiently to enable the lamp to swing outwardly when fully inserted without substantial axial movement whereby a lamp may be inserted therein by placing the lamp base in the inserting entrance of said insulating member and swinging the bulb end of said lamp inwardly into said casing, spring means for engaging the bulb and exerting axial pressure thereon to press the lamp center contact against the receptacle center contact, and a tubular bushing for the passage of the feed wires 100 secured to the end of the casing, said spring having a base portion secured to said bushing.
